(57) **CLAIM**

The ornamental design for an ice level sensing member, as shown and described.

DESCRIPTION

FIG. 1 is a right front perspective view of the sensing member of the invention;

FIG. 2 is a right side elevational view of the sensing member of FIG. 1;

FIG. 3 is a left side elevational view of the sensing member;

FIG. 4 is a rear elevational view of the sensing member;

FIG. 5 is a front elevational view of the sensing member;

FIG. 6 is the top view of the sensing member; and,

FIG. 7 is a bottom view of the sensing member.
